UNITED STATES PATENT OFFICE

2,523,220

PASTE APPLYING DEVICE

John Klesper, Milwaukee, Wis.

Application June 2, 1947, Serial No. 751,660

2 Claims. (Cl. 91—14)

1

My invention relates to paste applying devices and more particularly to portable means for applying an adherent agent to one side of wall paper or the like.

The object of my invention is to provide a portable device to convey paste to one side of paper supported in a roll by the device.

Another object of my invention is to provide such a device that will apply a pre-determined thickness of paste to one side of the paper and distribute it evenly over the entire surface of one side of the paper.

A still further object of my invention is to provide a device that incorporates a means for severing the paper at any pre-determined length.

Still another object of my invention is to provide a device that is constructed in a manner to permit the component parts to be easily removed for cleaning purposes.

It is manifest to anyone familiar with the use of rolled wall paper, that it is sometimes quite a laborious and inconvenient procedure to apply an adhesive agent to one side of the paper and to cut the paper to a pre-determined length. With the device illustrated, described and claimed herein the paste or adherent agent may be conveniently conveyed to the paper and the paper may be fed or pulled over a coating roll and the surplus paste or adhesive agent may be removed prior to the paper being cut to length.

The device may be easily transported and forms a compact unit having all the component parts arranged in a manner to permit their being mounted and replaced without the use of special tools or the like.

Other and further objects of my invention will become more apparent as the description proceeds and when taken in conjunction with the drawings in which

Figure 1 is a perspective view of the entire unit in a closed position arranged for transporting.

Figure 2 is a top or plan view of the device in an open position showing the support for a roll of paper extending outward therefrom.

Figure 3 is a cross-sectional view of the assembled device with a roll of paper mounted outward therefrom and having the paper arranged for contact with the paste roller and the comb arrangement.

Figure 4 is a fragmentary cross-sectional view of the roller and comb arrangement with the paper shown in phantom passing over the comb.

Figure 5 is a fragmentary cross-sectional view of the front portion of the container illustrating the manner in which the cover may be held open

2

in any position in its relation to the reservoir or lower part of the assembly.

Figure 6 is a side view of the paper roll support.

Figure 7 is a fragmentary perspective view of a portion of the comb, and

Figure 8 is a fragmentary view of a roller bearing arrangement showing the resilient retaining means employed for keeping the ends of the roller shaft in engagement with the bearings.

10 Similar characters of reference indicate corresponding parts throughout the several views and referring now to the same, the character 10 shows the lower portion of the device forming an enclosure or reservoir into which the paste or adherent agent shown as 11 is placed. This lower portion or container 10 is provided at one of its ends with a drain plug shown as 12 which threadedly engages the wall of the container 10. The front end of the container 10 is provided with an inwardly extending ledge or shelf arrangement 13 which is shown integrally formed with the outside wall of the enclosure 10. There is a cover unit shown as 14 which is hingedly attached to the reservoir 10 by means of a piano hinge 15 or in any other convenient manner. The cover portion 14 is provided at its rearward end with a pivotally supported door 16 which is disposed to swing outward and may have its lower edge 17 serrated for severing, cutting or tearing wall paper or the like shown as 18 which passes through the device.

20 There is a main paste applying roll 19 which is mounted in bearings 20 and 21 in the reservoir section 10 of the unit. The one bearing 20 is annular in construction and the other bearing 21 is of semi-radial contour as shown in Figure 8, and there is a resilient member 22 attached to a block 23 supported by the inner face of the end wall of the reservoir 10. This resilient member

25 22 is disposed for retaining the shaft 24 of the roll 19 in engagement with the bearing 21 while the device is in use, and when the roll 19 is to be removed for cleaning it is merely necessary to move the resilient member 22 upward or it may be pivotally mounted so it can be moved sideways to release the end of the shaft 24 so that the roller 19 can be removed.

30 I show a pair of outwardly extending brackets 25 which is provided with a hook portion 26 engaging the shelf or ledge 13 of the reservoir 10 and which is attached to the outer wall of the reservoir 10 by means of a screw 27. The details of this support member 25 are shown in Figure 6. It is arranged for supporting a rod 28 onto which the roll of paper shown as 29 is

mounted, and as the end of the paper 29 passes through and between the cover 14 and the ledge 13, a pair of eccentric levers 30 shown pivotally mounted at 31 may be moved to raise or lower the cover member 14 to permit the paper 18 to enter the entire unit.

The cover member 14 is also provided with a small roller 32 which is longitudinally disposed within the cover and is located at a point near the outer peripheral surface of the main roller 19 onto which the paste adheres as it is being revolved. This small roller 32 has for its purpose keeping the paper 18 in engagement with the upper portion of the roller 19 onto which the paste 11 has been applied.

There are also two auxiliary rollers 33 and 33' which are longitudinally disposed and mounted on shafts 34 and 34' which are journaled in bearings within the wall of the cover member 14. These two auxiliary rollers 33 and 33' have for a purpose keeping the paper 18 in frictional engagement with a comb member shown as 35 which is longitudinally disposed adjacent to the auxiliary rollers 33 and 33' when the device is in a closed position.

This comb member 35 is hingedly supported by the walls of the reservoir member 10 and consists of a plurality of fingers or spaced members 36 which contact the paste or adhesive agent on the bottom of the paper 18 where it has been placed by the rotation of the paste roller 19. The rearward wall 37 of the comb member 35 is not slotted and is employed for brushing off the excess plate where the spaced members 36 of the comb 35 will distribute the paste evenly along the surface of the paper, the rear wall 37 of the comb member 35 will permit the comb 35 to be pivotally adjusted as shown in Figure 4, and this adjustment will determine the amount of paste that will be retained on the lower surface of the paper 18 as it passes over the comb 35.

The paper 18 is permitted to leave the hinged or pivotally mounted door 16 at the rearward end of the cover 14 where it is pulled by the operator, and as the paper 18 is pulled through the entire device it will pass over the paste roller 19 and will be taken from the roll 29 suspended by the bracket 25 in the forward end of the entire unit.

It will be manifest to anyone familiar with the art that this type of device is very compact in its construction and may be assembled and disassembled for use in a comparatively short period of time. It will also be noted that I show a pair of resilient clamp members 39 which are attached to the inside of the top of the cover member 14 and are employed to retain the rod 28 onto which the roll of paper 29 is applied. It will also be noted that the brackets 25 may be adjustably and slidably moved sideways, either apart or toward one another to guide the paper and support the various widths of paper that may be used and put through the device.

The construction of the comb member 35 is such that the quantity of adhesive agent applied to the paper may be governed by having the individual prongs or sectional members 36 contacting the paste on the bottom of the paper 18. This will cause the paste to be spread evenly over the entire surface, and the rear wall 37 of the comb member 35 will cause the surplus paste to be scraped off the paper and deposited back into the reservoir 10 where it will be used over again.

In the chosen embodiments of my invention there are many features not heretofore disclosed

in the prior art and although I have shown a specific arrangement of the component parts, I am fully cognizant of the fact that many changes in the form and configuration of the component parts may be made without effecting their operativeness and I reserve the right to make such changes as I may deem necessary or convenient without departing from the spirit of my invention or the scope of the appended claims.

10 Having thus described my invention what I claim and desire to secure by Letters Patent in the United States is:

1. A device of the character described to be used with a roll of paper, said device comprising an enclosure horizontally disposed, said enclosure separated horizontally near its center and having the upper and lower portion thereof hingedly attached at their rearward end, said bottom portion employed as a reservoir for an adherent agent disposed therein, a main roll removably and rotatably journaled within the walls of said reservoir in a manner to allow only the lower portion of said roll to be submerged in an adherent agent disposed within said reservoir, an inwardly extending ledge forming a part of the front wall of said reservoir, a removable shaft, a pair of removable support brackets, acting as a means attached to the front of said reservoir for supporting said shaft, said shaft longitudinally disposed along the front of said reservoir for supporting a roll of paper, a front roller longitudinally disposed forward from said main roll, said front roller rotatably mounted at both of its ends to the walls of the upper portion of said enclosure, a pair of auxiliary rolls mounted in bearings supported by said upper portion at a point rearward from said main roll, a longitudinal comb member mounted pivotally at a point between said auxiliary rolls near the upper portion of said reservoir, means attached to said comb member for varying the angular relation of said comb within said auxiliary rolls, said comb member constructed of a sheet of material angularly disposed and arranged in a manner to provide a front face, a rear face and a top face, said top and front face slotted with a plurality of notches arranged at right angle to the longitudinal structure of said comb, said rear face being without slots to a point at its juncture with the upper face thereof, a longitudinal door member mounted on the rear wall of the upper portion of said enclosure, said door member hingedly supported at its upper edge to the rear wall of said upper portion and having its lower edge serrated, means extending through the wall of said reservoir for draining the adherent agent from said reservoir, and means for adjustably supporting the upper portion of said enclosure in its relation to the reservoir to provide a pre-determined opening 60 for the paper to enter the device.

2. A device of the character described to be used in combination with a roll of paper, said device comprising an enclosure horizontally disposed, said enclosure separated horizontally near its center and having the upper and lower portions thereof hingedly attached at their rearward end, said bottom portion employed as a reservoir for an adherent agent disposed therein, a main roll journaled within said reservoir, a removable shaft, a pair of removable adjustable support brackets, said shaft to be journaled within the support brackets in a manner to allow a roll of paper to be rotatably mounted therein, a front roll, said front roll rotatably mounted at both its ends to the walls of the upper portion of said

enclosure forward from said main roll, a pair of auxiliary rolls mounted in bearings supported by said upper portion at a point rearward from said main roll, a longitudinal comb member mounted pivotally near the upper portion of said reservoir at a point between said auxiliary rolls mounted in said upper portion, said comb member constructed of a sheet material angularly disposed and arranged in a manner to provide a front face, a rear face and a top face, said top and front faces slotted with a plurality of notches arranged at right angle to the longitudinal structure of said end, said rear face being without slots to a point at its juncture with the top face thereof, a longitudinally disposed door member, said door member supported at its upper edge to the rear wall of said upper portion and having its lower edge serrated.
